Primary Examiner — Sandra L Morris(74) *Attorney, Agent, or Firm* — Chris J Katopis(57) **CLAIM**

The ornamental design for a sunflower-style container lid, as shown and described.

DESCRIPTION

FIG. 1 is a front perspective view of a sunflower-style container lid, showing the new design;

FIG. 2 is a front view thereof;

FIG. 3 is a rear view thereof;

FIG. 4 is a side view thereof;

FIG. 5 is the opposite side view thereof;

FIG. 6 is a top plan view thereof; and,

FIG. 7 is a bottom view thereof.

In all figures, the broken lines showing the environmental subject matter and/or portions of the lid are included for illustrative purposes and form no part of the claimed design.
